(Cl. D54—2)

Fig. 1.

Fig. 2.

To all whom it may concern:

Be it known that I, Franz Wagner, a citizen of the United States, residing at Chicago, county of Cook, and State of Illinois, have invented a new, original, and ornamental Design for Sheet Metal, of which the following is a specification, reference being had to the accompanying drawing, forming part thereof.

Fig. 1 is a plan view of sheet metal, showing my new design.

Fig. 2 is an enlarged fragmentary section of said article taken on line 2—2 of Fig. 1 in the direction of the arrows.

I claim:

The ornamental design for a sheet metal, as shown.
